UNITED STATES PATENT OFFICE.

ARTHUR W. COX, OF AUBURN, MAINE, ASSIGNOR OF ONE-HALF OF HIS
RIGHT TO DANIEL M. MAHONEY, OF BRISTOL, RHODE ISLAND.

BOOT-TREE.

SPECIFICATION forming part of Letters Patent No. 224,517, dated February 17, 1880.

Application filed September 22, 1879.

To all whom it may concern:

Be it known that I, ARTHUR W. COX, of Auburn, county of Androscoggin, State of Maine, have invented an Improvement in Boot-Trees, of which the following description, in connection with the accompanying drawings, is a specification.

This invention relates to boot-trees more especially adapted to the manufacture of india-rubber boots; but the invention is applicable to trees for other kinds of boots.

In this my invention the boot-tree is shown as composed of cast metal, and, in accordance with my invention, the leg and foot are made hollow and sectional, or in two or more parts, in order that they may be readily cast without the use of cores, and the foot, adapted to at the proper time be fixed in position at the lower end of the leg, is so joined with a flexible connecting device—a chain, wire, or thong—as to permit the foot to be moved out of its fixed engagement with the leg and turn to occupy a position at the end of the leg, as denoted in dotted lines, whereby the leg and foot may be readily and easily drawn from the boot at the proper time, when the foot may be quickly turned and fixed in position upon the leg, the connecting device being then fastened to hold the foot in proper engagement with or in proper position upon the leg.

Figure 1 represents, in side elevation, in full lines, a boot-tree containing my invention, a part of one-half of the leg being broken away to show the interior of the other half, and the dotted lines showing the foot dropped to the end of the leg, as it will be when withdrawing the tree from the boot; and Fig. 2 is a bottom view of the leg and foot.

The boot-leg is shown as composed of two metal shells, *a b*, preferably cast-metal shells, secured or fixed together by means of rivets or bolts *c d*.

The lower front part of the leg has a flat face, as denoted by the line *e*, and a slot or recess of suitable width to receive the keel *f* of the foot *g*, the said keel at its upper portion having a tapering projection, *h*, to engage a portion, *i*, of the shell of the leg, as in Fig. 1, the upper end, *j*, of the foot bearing against

the flat face of the leg, thereby preventing the foot from being turned away from the leg until after it has been moved a short distance on the leg in the direction of the arrow on the foot, when it may be turned into the position shown in dotted lines, Fig. 1. This foot part cannot, however, be so moved or turned until after it is released by disengaging the attaching-hook or equivalent, *l*, of the foot and leg connecting device *m*, preferably made as a chain, and flexible, while the hook will preferably be a spring-hook, to engage an adjustable plate or projection, *n*, attached to the leg.

The lugs or ears *o o*, attached to the inner sides of the leg parts *a b*, are provided with holes 2 to receive a pin, by which the boot-leg 65 may be kept in upright position when being subjected to the curing-heat necessary for india-rubber boots.

The foot *g* is composed of two shells, 4 5, connected together by a rivet or bolt, 6, and 70 rivets 7 8.

The boot-tree is very light as compared with some other trees, is very strong, easily made, and easily manipulated.

It is obvious that my method of applying 75 the foot to the leg and releasing it so as to be turned aside may be practiced to advantage in a tree wherein the leg was cast in one piece with a core, and also with the foot so cast, or with other usual form of foot.

The form of the attaching device *l* may be changed without departing from my invention, and, if desired, I may connect with the ring part of *l* a small wire or chain, as at *p*, which will prevent the attaching device falling too low to be readily picked up by the finger, or so that the foot becomes completely detached from the leg.

I claim—

1. As an improved article of manufacture, 90 a boot-tree composed of a shell-like leg and foot, fitted together as described, and a flexible connecting device, to hold the foot and leg together and permit the foot to be disengaged from the leg and turned, as desired, to the 95 end of the leg, substantially as described.

2. The combination, with the foot and leg, fitted together substantially as described, of

the flexible connecting device and a hook to readily engage it with and disengage it from the leg, substantially as described.

3. A boot-tree composed of a two-part metallic shell-like leg and a two-part metallic shell-like foot, the foot and leg being connected by a keel and slot, substantially as described.

In testimony whereof I have signed my name to this specification in the presence of or two subscribing witnesses.

ARTHUR W. COX.
